[57] **CLAIM**

The ornamental design for a chair, as shown and described.

DESCRIPTION

FIG. 1 is a perspective view of a chair showing my new design;

FIG. 2 is a right side view thereof, the left side being a mirror image;

FIG. 3 is a front view thereof;

FIG. 4 is a top view thereof;

FIG. 5 is a perspective view of a second embodiment of my new design;

FIG. 6 is a front view thereof;

FIG. 7 is a perspective view of a third embodiment of my new design; and,

FIG. 8 is a perspective view of a fourth embodiment of my new design.

The rear view of each embodiment has not been shown and forms no part of the claimed design.

The opposite ends of FIGS. 5, 7 and 8 are mirror images of what has been shown.

1 Claim, 8 Drawing Sheets
